UNITED STATES PATENT OFFICE.

INOSUKE TSUCHIYA, OF SAUSALITO, CALIFORNIA.

DESIGN FOR A GARDEN-RAKE.

54,878.

Specification for Design.

Patented Apr. 13, 1920.

Application filed October 4, 1919. Serial No. 328,600. Term of patent 14 years.

To all whom it may concern:

Be it known that I, INOSUKE TSUCHIYA, a citizen of Japan, residing at Sausalito, Marin county, State of California, have invented a new, original, and ornamental Design for Garden-Rakes, of which the following is a specification, reference being had to the accompanying drawing, forming part thereof, wherein—

The figure is a view in perspective of a rake illustrating my new design.

I claim:

The ornamental design for a garden rake as shown.

In witness whereof I have signed my name to this specification in the presence of two witnesses.

INOSUKE TSUCHIYA.

Witnesses:

HARRY A. TOTTEN,
D. B. RICHARDS.
